COMBINED FISHING ROD SUPPORT AND ALARM MOUNT

Harry S. Ardizzone, 1648 N. Alabama St. 46202, and
Graydon W. Rynard, 3947 N. Adams, Apt. 244, 46205,
both of Indianapolis, Ind.

Filed June 21, 1967, Ser. No. 7,539

Term of patent 14 years

(Cl. D22—22)

Fig. 1.

Fig. 2.

Fig. 3.

FIG. 1 is a side elevational view of a combined fishing rod support and alarm mount, showing our new design.

FIG. 2 is a rear elevational view thereof.

FIG. 3 is a front elevational view thereof.

The dominant features of our design reside in the portions shown in full lines.

We claim:

The ornamental design for a combined fishing rod support and alarm mount, as shown and described.
